US00D564897S

(12) **United States Design Patent** (10) **Patent No.:** **US D564,897 S**
Trollope et al. (45) **Date of Patent:** **** Mar. 25, 2008**

(54) **BOTTLE**

(75) Inventors: **James D. Trollope**, Frisco, TX (US);
Blair C. Dugger, Frisco, TX (US);
Kendall L. Yorn, Allen, TX (US); **Alan Flude**, London (GB)

(73) Assignee: **Dr Pepper/Seven Up, Inc.**, Plano, TX (US)

(**) Term: **14 Years**

(21) Appl. No.: **29/249,396**

(22) Filed: **Oct. 4, 2006**

(51) LOC (8) Cl. **09-01**

(52) U.S. Cl. **D9/652; D9/552; D9/556**

(57) **CLAIM**

The ornamental design for a bottle, as shown and described.

DESCRIPTION

FIG. 1 is a top plan view of a bottle showing our new design;

FIG. 2 is a front elevational view thereof;

FIG. 3 is a right side elevational view thereof;

FIG. 4 is a rear elevational view thereof; and,

FIG. 5 is a left side elevational view thereof.

The oblique shade lines shown in the drawings represent that the bottle is transparent.
